United States Patent Office.

ANDREW SMITH, OF DAYTON, OREGON.

Letters Patent No. 80,228, dated July 21, 1868.

IMPROVEMENT IN HORSE-POWER.

The Schedule referred to in these Letters Patent and making part of the same.

TO ALL WHOM IT MAY CONCERN:

Be it known that I, ANDREW SMITH, of Dayton, in the county of Yam Hill, and State of Oregon, have invented a new and useful Improvement in Horse-Power; and I do hereby declare that the following is a full, clear, and exact description thereof, which will enable others skilled in the art to make and use the same, reference being had to the accompanying drawings, forming part of this specification, in which—

Figure 1 is a plan or top view of my invention.

Figures 2 and 3 are vertical sections of a portion of the same, taken respectively in the lines $x x$, $y y$, fig. 1.

Similar letters of reference indicate corresponding parts.

This invention relates to a new and improved horse-power, in which belts are employed, instead of gearing, for transmitting the power from the driving-wheel to the shaft from which the power is taken. The invention is designed for a portable machine, which may be readily put up and taken down, and readily kept in repair by any person of ordinary ability.

In the accompanying sheet of drawings, A represents a suitable frame, in which a vertical shaft, a , is firmly secured, having a wheel, B, keyed upon it, to which a sweep, C, is attached, the rim of the wheel B resting or bearing upon anti-friction rollers, b , as shown clearly in fig. 1.

D is a driving-belt, which passes around the wheel B, and is made to hug the periphery of said wheel by means of two vertical rollers, $c c$, as indicated by the dotted lines in fig. 1.

This frame A is staked to the ground in any suitable way.

E is a frame, in which a vertical shaft, d , is fitted, and on which a wheel, F, is keyed, around which the driving-belt D passes. This shaft d is adjustable in the direction indicated by the arrows 1 1 and 2 2, (see fig. 1,) the bearings e of the shaft d being connected by a bracket, F, in which a screw, G, is fitted, and by turning which the bearings may be moved in the direction of the arrows 1.

The bearings e are fitted in slides H H, which are connected by a bracket, I, in which a screw, J, is fitted, and, by turning this screw, the bearings may be moved in the direction indicated by the arrows 2. By moving the bearings in the direction indicated by the arrows 1, the driving-belt D may always be kept at a proper degree of tension.

In the frame E there is also fitted a vertical shaft, K, having a pulley, L, upon it, and also a wheel, M.

A belt, N, passes around the pulley L, and also around a wheel, O, in the shaft d , above wheel F.

By moving the slides H H, through the medium of the screw J, the belt N may be tightened and kept at the proper degree of tension.

The horse is attached to the sweep C, and rotates the wheel B, in passing around frame A, a bridge being placed over the driving-belt D, for the horse to walk over. The power is taken from the wheel M.

The advantage of this invention consists in the simplicity of its construction, the moderate cost of manufacture, and the facility with which it may be kept in repair by any person of ordinary mechanical ability.

Having thus described my invention, I claim as new, and desire to secure by Letters Patent—

The shaft d , in the frame E, arranged so as to be capable of being adjusted in two different directions by means of the screws J G, connected respectively with the slides H and bearings e , as indicated by the arrows 1 2, in combination with the frame A, containing the driving-belt D and rollers $c c$, and the belt N, with the shaft K in frame E, all arranged for joint operation, substantially in the manner as and for the purpose set forth.

ANDREW SMITH.
